(57) **CLAIM**

We claim the ornamental design for a sealable pourer, as shown and described.

DESCRIPTION

FIG. 1 is a right side isometric view of one embodiment of cap for a sealable pourer showing our new design;

FIG. 2 is a left side isometric view thereof;

FIG. 3 is a front elevation view thereof;

FIG. 4 is a rear elevation view thereof;

FIG. 5 is a top view thereof;

FIG. 6 is a cross-section taken along line 6-6 in FIG. 3;

FIG. 7 is a cross-section taken along line 7-7 in FIG. 5; and,

FIG. 8 is a bottom view thereof.
